CHANCE GAME DEVICE

Sidney P. Johnson, Washington, D. C.

Application July 30, 1954, Serial No. 446,781

2 Claims. (Cl. 273—147)

My invention relates to chance or game devices for use with games, such as for example, backgammon and other games, that require a plurality of prismatic members of the nature of dice. These prismatic members are hereinafter called dice or dies in the plural and die in the singular for convenience and because of the lack of a simple designation in the language therefor.

A principal object of the invention is to provide a unitary device containing a pair of dice with numbered or marked faces or flats; the device being operable by hand to provide an unpredictable and uncontrolled display of a chance combination of dice numbers or marks.

A further object of the invention is to provide a single unit device of a type described which will rapidly come to a stop and display a score or groups of scores for one or more players.

The preferred form of a game device in accordance with the invention is in the nature of a top having a whirl-head by means of which it can be whirled or manually set into spinning motion on its tip, preferably on a flat surface. The game device spins until its spinning momentum or gyroscopic force is insufficient to keep it upright; whereupon it falls sidewise to a stationary position with its chance display facing upward. To obtain the chance display the device comprises a pair of hexagonal die members or dice, each having number-indicia from one to six on its six faces. These die members also rotate while the game device rotates; but the device is so constructed that the members will rotate haphazardly and independently so that they provide one or more chance displays when the device topples over and stops.

The foregoing and other objects of the invention will be apparent from the following description of a preferred form thereof to which the invention in its broadest aspect is not limited. The description is to be taken in conjunction with the accompanying drawings which are substantially to scale. In the drawings:

Fig. 1 is a side view of the whirl-head end of a device in accordance with the invention; the device being at rest on a horizontal supporting plane indicated by the line A—A;

Fig. 2 is a plan view of the device shown in Fig. 1; the device being shown at rest on a horizontal supporting plane which corresponds to the plane of the drawing paper;

Fig. 3 is a sectional instantaneous view of the device, the device being in an upright position with its extreme lower tip on the horizontal supporting plane indicated by the line A—A;

Fig. 4 is a sectional view of a modified detail of the invention; and

Figs. 5—11 are views for illustrating the principle of operation of a device in accordance with the invention, the views showing successive positions of the device as it topples from an upright spinning position to stationary horizontal display position.

The device shown in the drawings comprises a central shaft 2 of any suitable material, preferably a metal such as, for example, stainless steel or aluminum. The shaft 2 has a pointed or rounded spin-tip 4. A weighting member or flywheel 6, in the preferred form of a section of a sphere, is press fitted or otherwise fixed to the shaft 2 somewhat above the spin-tip 4. The flywheel member 6 is somewhat less than a semi-sphere and has an upper

2

face 8 having a circle as a periphery. The maximum horizontal diameter of the member 6 bears a relation to the die members subsequently described. In the embodiment shown this diameter is that of the circular face 8.

5 The flywheel member 6 also acts as a support or spacing member for a first washer 10 on the shaft 2. Above the washer 10 the shaft 2 successively holds, as shown in Fig. 3, a first die member 12, a second washer 14, a second die member 16, and a third washer 18. A knurled whirl-head 20 is press fitted onto the top end of the shaft 2. The bottom of the head 20 is spaced from the face 8 of the flywheel member 6 a distance somewhat greater than the sum of the thicknesses of the three washers 10, 14 and 18, and the two dice 12 and 16.

10 The first washer 10 has a center hole which just about fits the shaft 2 so that the washer lies flat on the face 8; but the washers 14 and 18 and the die members 12 and 16 have somewhat oversize center holes so that they can 15 rotate about the shaft 2 as an axis.

The die members 12 and 16 have the same size and 20 shape, being hexagonal prismatic members. Each has a pair of parallel bases and six outer flats or faces 22. Each base is in the form of a regular hexagon. Preferably, the thickness and size of each die member is chosen 25 to make the faces 22 square, but they can be rectangular or other suitable shape. The six faces or flats of each die member have different indicia thereon, the indica representing numbers from one to six as in the conventional die. The arrangement of the indicia on one die member 30 differs from that on the other so as to provide a sum of seven on all pairs of two aligned faces of the dice when the dice are rotated relative to each other to the proper position. A satisfactory arrangement of number-indicia 35 on consecutive faces of the die members is as follows:

One die—1, 4, 5, 2, 3, 6.

Other die—6, 3, 2, 5, 4, 1.

The die members 12 and 16 may be of the same material, a colored plastic being preferred with the indicia impressed therein and subsequently clearly visibly painted.

In accordance with the invention, the game device is 40 constructed to cause the dice 12 and 16 to rotate relative to each other in a chance manner when the device is spun. This is accomplished by having the washers 10 and 14 of different coefficients of friction. For example, the washer 10 can be made of cork or rubber, and the washer 14 of brass. The washer 18 can be identical with the washer 14.

To permit the game device to topple over and rest on a 45 pair of flats or faces 22 of the dice 12 and 16, the maximum thickness of the flywheel member 6 in a direction perpendicular to the shaft 2, in this case the diameter of face 8, is less than the minimum dimension perpendicular to the shaft 2 of the dice 12 and 16; this last dimension corresponds to the distance between a pair of parallel sides of the hexagonal periphery of a base of the dice 12 and 16. As an indication of this construction, in a 50 specific embodiment of the invention as shown in the drawing, the minimum dimension of a die member was one inch while the diameter of the face corresponding to face 8 was seven-eighths inch. This means that the die members extend radially beyond or "overhang" the flywheel 6 at every radial point thereof. In this sense, the die members overhang all the remaining parts of the game device.

For operation, the game device may be held upright 55 with its tip 4 resting on a table or other generally level surface as represented by line A—A in Figs. 1 and 3, and with its whirl-head 20 between the thumb and forefinger of a hand of a player. The device is spun or whirled by suitable movement of these fingers in known

manner for tops of this general kind. While the device spins rapidly it remains upright; but upon losing enough momentum it topples over onto an edge of the lower die member 12. The most stable rest position of the dice is flat on a face of each of the dice 12 and 16. The device comes to rest in such a position where the faces opposite those on which the device rests are level and face upward, as shown in Fig. 2. The sum of the indicia on these two level faces represent the chance display made by the player.

During the acceleration, rotation and deceleration of the game device, the die members 14 and 16 rotate relative to each other in an unpredictable manner. I believe this to arise from the different frictional characteristics of the washers 10 and 14. During spinning of the device, the lower die member 12 engages or is in contact with washer 10, and upper die member 16 is in contact with washer 14. Because of the difference in the frictional characteristics of the washers, the upper die member 16 at some period or periods during spinning of the device rotates at a different speed from the die member 12; that is, the die members rotate relative to each other. The amount of relative rotation is completely unpredictable, and is a matter of chance. This relative rotation apparently takes place primarily during acceleration and deceleration of the device. It is also possible that relative rotation is influenced by the fact that the upper die member 16 bears on the lower die member 12 through washer 14, thereby causing both bases of the die member 12 to be acted upon by pressure forces, whereas only the lower base of the upper die member 16 is so acted upon.

When the game device topples over, two faces, one on each die member, are flat and on top, as indicated in Fig. 2, and the indicia thereon indicate the player's score or display, as previously described.

The manner of playing the game is subject to many variations. Thus, one player may have the indicia on the two top flat horizontal faces as his score. A second player can have the indicia on the two faces slanting from one side of the horizontal faces as his score; and the third player can have the indicia on the other two faces slanting from the horizontal faces as his score. Thus, a single operation of the device provides a score for more than one player. By also coloring some or all of the faces differently, further distinct combinations of pairs of faces can be chosen by players, so that several players can have scores from a single operation of the device. For example, the faces on each die could be colored consecutively white and red, or red, white, yellow, red, white, yellow.

In the embodiment of Figs. 1-3, the whirl-head 20 is shown press fitted onto the end of shaft 2. However, the whirl-head may be attached to the shaft in any suitable manner; and is shown in Fig. 4 as being screwed to the shaft. The latter construction permits ready disassembly and assembly of the die members and washers on the shaft.

Figs. 5-11 illustrate the operation of the device as I have observed it. In these figures, comparatively stationary parts are indicated by being shaded.

The whirl-head 20, central shaft 2, and the flywheel 6 are constructed to be unitary, being rigidly held together. When the device is held vertically for spinning the lower die member 12 rests on the lower washer 10 which rests on the face 8 of the flywheel. The middle washer 14 rests on the lower die member 12, and the upper die member 16 rests on this washer. There is a clearance between the top washer 18 and the whirl-head 20.

The only turning force that can be applied to the lower die member 12 arises from the friction forces between the rotating flywheel 6, the washer 10 and the die member. The possible friction from the shaft 2 to the die members can be neglected because of the oversize holes in the die members. Similarly, the turning force for die member

16 comes from the friction forces arising through washer 14. Consequently, all parts do not come up to spinning speed at the same time, thus introducing elements of chance.

Further elements of chance occur in the sequence that the device undergoes in toppling over after enough energy of rotation has been dissipated.

The first action in falling is indicated in Fig. 6 where the assembly slithers on the spin-tip 4 and a tangent point on the flywheel surface.

As the device topples further, the device tends to fall or roll further up on the curved surface of the flywheel as shown in Fig. 7. This occurs until a corner of the lower die member 12 strikes the surface A—A on which the device has been spinning. This is shown in Fig. 8. The lower die member 12 tends to stop spinning, but the upper die member 16 continues to spin relatively rapidly.

The lower die member moves on its corner until a full edge of one of its faces rests on the surface A—A, as indicated in Fig. 9. The device pivots on this edge as continued toppling of the device brings the upper die member 16 nearer to the surface A—A as shown in Fig. 10; and the device stops with the top faces of the two die members horizontal with the surface, as indicated in Fig. 11.

Thus there are many independent elements of uncontrolled chance in the act of spinning the device and its toppling to a rest position.

While I have described my invention in one of its preferred embodiments, it is obvious that the teaching thereof can be applied in various other embodiments within the scope of the invention and claims.

I claim:

1. A spinnable game device in the nature of a top, comprising a spin tip on one end and a whirl head on the other, a shaft portion between said ends, a pair of physically similar die members loosely mounted on said shaft portion for rotation relative thereto and to each other, each of said die members having a hexagonal periphery in a cross section perpendicular to said shaft portion and six faces substantially parallel to said shaft portion, said six faces having different number indicia thereon from one to six, said die members radially overhanging the remaining parts of said game device, a weighting member at the lower end of said shaft below said die members, the largest diametrical dimension of said weighting member being only slightly less than the distance between parallel faces of a die member, and washers formed of material having different coefficients of friction for torque transfer to each of said die members whereby to effect variation in rotational speeds between said die members during operation of said game device, said weighting member having a convexly curved outer surface.

2. A game device comprising a shaft provided with a spin tip at one end and a whirl head at the other end, a weighted member for effecting angular momentum adjacent said spin tip, a plurality of polygonal prisms rotatably mounted on said shaft intermediate said weighted member and said whirl head, said prisms being independently rotatable, a first washer intermediate said weighted member and one prism, a second washer intermediate said one prism and the other prism, wherein when said device is spun said one prism rests on said washer and said other prism rests on said second washer, said washers being of materials having different coefficients of friction to thus effect rotary speed variation of said prisms.
